US0D1083932S

(12) **United States Design Patent** (10) **Patent No.:** **US D1,083,932 S**
(45) **Date of Patent:** **** Jul. 15, 2025**

(54) **DOCKING STATION**

(71) Applicant: **Ugreen Group Limited**, Shenzhen (CN)

(72) Inventors: **Qingsen Zhang**, Shenzhen (CN);
Junling Chen, Shenzhen (CN);
Jingxian Cai, Shenzhen (CN)

(73) Assignee: **Ugreen Group Limited**, Shenzhen (CN)

(**) Term: **15 Years**

(21) Appl. No.: **29/907,146**

(22) Filed: **Jan. 4, 2024**

(51) LOC (15) Cl. **14-02**

(52) U.S. Cl.

USPC **D14/434**

(57) **CLAIM**

The ornamental design for a docking station, as shown and described.

DESCRIPTION

FIG. 1 is a front, top perspective view of a docking station, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the docking station, shown in an alternative position.

The broken lines in the figures illustrate portions of the docking station that form no part of the claimed design.

1 Claim, 9 Drawing Sheets
